UNITED STATES PATENT OFFICE.

FRANK M. MORTON, OF PHOENIX CITY, ALABAMA.

CALENDER RACK.

Application filed October 22, 1923. Serial No. 670,121.

To all whom it may concern:

Be it known that I, FRANK M. MORTON, a citizen of the United States, residing at Phoenix City, in the county of Lee and State of Alabama, have invented certain new and useful Improvements in Calender Racks; and I do declare the following to be a full, clear, and exact description of the invention, such as will enable others skilled in the art to which it appertains to make and use the same.

In textile mills, the stock is run through picking machinery to clean the same and produce a lap of uniform thickness. The stock at this stage is very light and fluffy, and in order to produce a compact lap or roll, the stock is wound by calender rolls onto a lap pin. This lap pin is held down at both ends by calender racks geared to a common shaft, the turning of which is retarded by a friction drum, weight and lever. In order to obtain the desired pressure on the lap pin, the correct amount of friction must be applied to the friction drum, but often the train of gears between the calender racks and the friction drum, becomes choked, or excessive friction is applied to the friction drum. In either instance, the pressure of the lap pin on the calender racks, becomes so great as to break said racks or other parts of the machine.

It is the object of my invention to prevent occurrences such as those above enumerated, by the provision of an improved rack, in which the lap pin bearing head is connected in a unique manner with the rack proper, so that when unusual tension is placed on these parts, the head is released from and slides on the rack.

A further object is to provide means for checking the sliding of the head on the rack, holding it until still greater strain is encountered and then again releasing the strain, if the machine is not given proper attention after the first sliding movement of the head takes place.

With the foregoing in view, the invention resides in the novel subject matter herein-after described and claimed, the description being supplemented by the accompanying drawing.

Figure 1 is a vertical sectional view partly in elevation, showing the normal relation of parts.

Figure 2 is a vertical sectional view on the irregular line 2-2 of Fig. 1.

Figure 3 is a duplicate of a portion of Fig. 1, but illustrating the manner in which the head is released from operative engagement with the rack.

In the drawing above briefly described, the numeral 1 designates an upright rack having teeth 2 for engagement with the usual gears or pinions. A head 3 is provided at the upper end of the rack 1 for engagement with the lap pin 4, said head having suitably mounted bearing rollers 5 and 6 to contact with said pin. From top to bottom, the head 3 is formed with a vertical guideway 7 which is laterally offset from the axes of the rollers 5 and 6, said guideway slidably receiving the straight upper end 8 of the rack 1, the relation of parts being such that the head may laterally shift upon the rack portion 8, when a predetermined amount of strain is upwardly exerted on said head (see Fig. 3).

In the construction shown, an angular metal plate 9, preferably formed of steel, has one of its arms 10 extended across and beyond the upper extremity of the rack 1, while the other arm of said plate extends downwardly along the side of the rack remote from the rollers 5 and 6. The lower end of the arm 11 constitutes a shoulder 85 which normally bears against a wear-plate 12 at the upper end of the guideway 7, thereby establishing an operative connection between the rack and the head 3. Strain-released means are provided, however, whereby the head 3 may laterally shift as shown in Fig. 3, to disengage the arm 11 from the wear-plate 12, thus permitting the head 3 to slide freely on the straight upper end 8 of the rack 1.

In the preferred form of construction, a horizontal guide 13 is formed in the upper portion of the head 3, said guide containing a plunger 14 and a compression spring 15 for forcing said plunger into contact with the upper end 8 of the rack 1. The strength of the spring may be adjusted as required by suitable means 16. This arrangement normally holds the head in operative relation on the rack, but permits lateral shifting of said head under excessive strain, as above set forth.

After disengagement of the arm 11 from the head 3, it will be seen that this head is free to slide upwardly upon the rack and if the machine is not then given the proper attention, the head will eventually contact

with the projecting end of the arm 10 which constitutes an abutment to again connect the head with the shank, permitting the machine to continue in operation as long as 5 the upward strain on the head 3 is below a second predetermined amount. When such excessive strain however is encountered, a bolt 17 which secures the plate 9 to the rack 1, is intended to break, thus giving a 10 second safety release.

It will be seen from the foregoing that I have provided a simple and inexpensive, yet an efficient and desirable arrangement of parts to prevent injury to any of the 15 elements of the machine, in case of severe upward strain upon the head 3. Furthermore, it will be seen that I have produced a calender rack having two safety releases, of obvious advantage.

20 As excellent results are obtainable from the details disclosed, they may be followed if desired, but within the scope of the invention as claimed, numerous modifications may be made.

25 I claim:

1. A device of the class described comprising a rack, a lap pin bearing head having a longitudinally slidable connection with said rack, inter-engageable elements carried 30 by said rack and said head to operatively connect said head to said rack and normally prevent said head from sliding upon said rack, and yieldable means to normally hold said elements in engagement, said means 35 being releasable when greater than normal pressure is applied to said head.

2. A device of the class described comprising a rack, a lap pin bearing head 40 slid-able on said rack and laterally shiftable with respect thereto, connecting means be-tween the rack and head releasable by said lateral shifting, and strain-releasable means for normally holding said head against such shifting.

45 3. A device of the class described comprising a rack, a lap pin bearing head slid-able on said rack and laterally shiftable with respect thereto, co-acting shoulders on the rack and head operatively connecting 50 them and disengageable from each other by lateral shifting of the head, and strain-releasable means for normally preventing such shifting.

4. A device of the class described comprising a rack, a lap pin bearing head hav-ing a guide slidably receiving said rack in a manner to permit lateral shifting of the

head on the rack, said rack having a shoulder contacting with one end of said guide and releasable therefrom by lateral shifting of 60 the head on the rack, and strain-releasable means for normally preventing such shifting.

5. A structure as specified in claim 2; said strain-releasable means comprising a 65 spring device acting on said head and re-acting on said rack.

6. A structure as specified in claim 4; said head having another guide transverse to and opening into the first named guide; said strain-releasable means comprising a spring device in said other guide acting against said head and re-acting against said rack.

7. A device of the class described comprising a rack, a lap pin bearing head on said rack movable from a normal working position to a second working position, strain-releasable means for holding said head in said normal working position, and strain-releasable means for checking said head when the latter moves to said second working position.

8. A device of the class described comprising a rack, a lap pin bearing head slidable on said rack and laterally shiftable with respect thereto, a shoulder on the rack for holding the head against sliding on said rack until laterally shifted, strain-releasable means for normally preventing such shifting, an abutment for checking the sliding of the head on the rack when released from said shoulder, and strain-releasable means securing said abutment to said rack.

9. A device of the class described comprising a rack, a lap pin bearing head having a guide through which one end of said rack passes slidably and in a manner to permit lateral shifting of the head on the rack, strain-releasable means for normally holding said head against such shifting, an angular plate having one arm extending across the end of said rack and projecting laterally from the latter in spaced relation with said head, the other arm of said plate extending along the rack into contact with said guide to hold the head against sliding until released by lateral shifting, and strain-breakable means securing said plate to said rack.

In testimony whereof I have hereunto affixed my signature.

FRANK M. MORTON.
